UNITED STATES PATENT OFFICE.

HIRAM H. CALVIN, OF TOLEDO, OHIO.

AIR-CONTROLLER FOR WARM-AIR FURNACES.

1,000,324.

Specification of Letters Patent. Patented Aug. 8, 1911.

Application filed August 6, 1910. Serial No. 575,958.

To all whom it may concern:

Be it known that I, HIRAM H. CALVIN, a citizen of the United States, and residing at Toledo, in the county of Lucas and State of 5 Ohio, have invented a new and useful Improvement in Air-Controllers for Warm-Air Furnaces, set forth in the annexed specification.

My invention relates to improvements in 10 air warmers by combining therewith a series of adjustable deflector plates interposed between the fire-box and the outer casing thereof; and the objects of my improvement are, first, to increase the absorption of 15 heat by the current volume of air; and, second, to equalize the temperature throughout the entire current volume.

I attain these objects by the mechanism 20 illustrated in the accompanying drawings, in which—

Figure 1 is a vertical section of an air warmer on the line Z. Z. Fig. 2; Fig. 3 is a horizontal section of same on line Y. Y. Fig. 1; and Fig. 3 is a view in perspective of the 25 indicator and its connection to the deflector plates.

Similar numerals refer to similar parts throughout the several views.

The outer casing 1, the fire-box 2, the free- 30 air inlet 8, and the warmed air outlets 9, are the constituent parts of an air warmer necessarily shown but for which no invention is claimed.

In my invention 4 designates a series of 35 adjustable interposed deflector plates by the combined eyelets and arbors 3 secured thereto and having bearings 3', radially concentric, in the fire-box and the outer casing and connected to each other by connecting 40 chains or rods 5 equidistant with the arbors. To the projecting end of the first in the series of arbors is loosely mounted the indicator plate 6 and secured to the outside of the casing 1; and rigidly secured to said 45 projecting arbor end is the combined lever and handle 7 in vertical alinement with deflector plate 4 to operate, support and indicate the vertical or any desired angular po-

sitions of the deflector plates and when released the plates attain a vertical position 50 by gravity.

I am not aware that, prior to my invention thereof, air warmers have been equipped with a series of deflector plates interposed at a height corresponding with the 55 hottest portion of the fire-box, and adjustable vertically and to any desired degree of angular position purposely causing the current volume of air passing through the air warmer to deflect from its natural vertical 60 and short travel to a circuitous and longer travel thereby absorbing an increased amount of the heat and more evenly tempered at each of the outlets.

I therefore claim:

The combination of an air warmer of circular form including a fire-box and a casing spaced therefrom with air inlet and air outlets thereto with an inner series of bearings spaced around and secured to the fire 70 box at the height of the heat zone thereof a corresponding series of outer bearings secured to the casing and concentric with the inner bearings to the fire box a series of arbors resting in said bearings a series of 75 deflector plates secured one to each of said arbors with their major portions being below the arbors so that the deflector plates will tend to a vertical position by gravity, a series of connecting rods or links of length 80 equal to the central spacing of the arbors and connected to the tops of the deflector plates one to each and all, with outward means attached to one of said arbors whereby to place and fix or release the deflector 85 plates in unison at or from any angular position desired, substantially as set forth.

In witness whereof I have hereunto signed my name in the presence of two subscribing witnesses, this 4th day of August, 90 1910.

HIRAM H. CALVIN.

In presence of—

RUFERT HOLLAND,
EDGAR M. HAWKINS.
